UNITED STATES PATENT OFFICE.

GEORGE W. FREEMAN, OF ST. PAUL, MINNESOTA, ASSIGNOR OF ONE-HALF TO JOHN E. STRYKER, OF ST. PAUL, MINNESOTA.

CONCRETE DAM.

1,043,761.

Specification of Letters Patent.

Patented Nov. 5, 1912.

Application filed August 14, 1912. Serial No. 715,014.

To all whom it may concern:

Be it known that I, GEORGE W. FREEMAN, a citizen of the United States, residing at St. Paul, in the county of Ramsey and State of Minnesota, have invented new and useful Improvements in Concrete Dams, of which the following is a specification.

My invention relates to an improvement in concrete dams. Its object is to provide a 10 dam having its decks formed of a plurality of concrete beams suitably supported and bonded together to form a unitary structure.

A further object is to provide means for 15 tying the deck beams to the buttresses of the dam to strengthen the structure and prevent any uplift of said decks.

A further object is to provide such a structure readily adaptable to the contraction and expansion of its parts.

20 My invention is particularly, though not exclusively, adapted for use in cold climates where if the concrete were molded *in situ*, it would be necessary to discontinue the work during the winter.

25 In the drawings, Figure 1 is a front elevation of the forward side of the dam embodying my invention; Fig. 2 is a sectional view of the same taken on the line 2—2 of Fig. 1; Fig. 3 is a detail sectional view taken 30 on the line 3—3 of Fig. 1, and Fig. 4 is a detail view showing a portion of a buttress in section, an end elevation of beams and means for tying the beams to the buttresses of a dam.

35 Referring to the accompanying drawings, I have used the reference numeral 10 to indicate the buttresses of the dam, which may be constructed *in situ* of any suitable material. The reinforced concrete toe 13, heel 40 14 and crown 15 are cast in place. The decks 16 and 16' consist of a plurality of deck-beams 17. These beams, bonded to each other and to said toe, crown and heel are tied to the buttresses 10 and form a 45 unitary structure. All of said members are reinforced by rods in the usual manner.

The beams 17 are molded separately at any convenient place and may be built on straight lines, as illustrated, or may be 50 curved to form either concave or convex deck sections between the buttresses of the dam. In the longitudinal corners of the upper surface of the beams 17, I mold a recess 18 to form key ways for the grouting material hereinafter specified. Each beam

is supplied with a looped rod 20 embedded in one end thereof and with a second looped rod 20' embedded in its opposite end. Sheet metal clips 21, secured to the buttresses 10 by embedded U bolts 22 and nuts 60 23, retain the anchor bolts 25 which pass through the looped rods 20 and 20' of abutting beams. Nuts 24 threaded on said bolts 25 are placed in positions above and adjacent to said rods 20 and 20'. By this means 65 I tie the beams to the buttresses 10 to secure stiffness and on the down stream deck to protect against any uplift which might otherwise occur. I prefer to slot the clips 21 to allow for variations in the width of 70 the beams 17.

The toe 13, heel 14 and crown 15 are each formed with a recess 18 similar to those which form key ways in the beams 17. The beams are arranged to rest at their ends on 75 adjacent buttresses and are spaced apart from each other at their ends and sides and from said toe, heel and crown. Grouting material 26 is then applied to the corrugated faces 10' of the buttresses 10, to the 80 spaces between said beams, toe, heel and crown including and filling the key ways formed by the recesses 18. I thus unite all of the parts of the dam into a strong structural unit. 85

I have provided for a slight movement of one end of each deck beam to allow for its contraction and expansion. To this end the loops of the rods 20 are wound with oakum or a like resilient wrapper 27 to prevent 90 close contact of the grouting with said rods, thus permitting a slight expansion and contraction of the beams. The base at one end of each beam is faced with a wood or fiber sheet 28 to prevent the grouting material 95 from binding said end to its supporting buttress and thereby provide a sliding joint. At each slideable end of said beams is a compressible wood or fiber sheet or plate 29 which permits a slight longitudinal movement of said beams. 100

My invention is advantageous for the reason that large forms or molds commonly used in the construction of a monolithic concrete dam may be eliminated and for the 105 further reason that the deck beams may be conveniently constructed during any season of the year in a limited space on shore, and thereafter placed in position and bound together to form the desired structural unit. 110

What I claim as new and desire to protect by Letters Patent is:

1. A dam comprising a plurality of buttresses built *in situ* and decks on said buttresses consisting of separately molded concrete beams bonded to each other and to said buttresses.

2. A dam having a plurality of concrete buttresses molded *in situ*, decks on said buttresses consisting of separately molded concrete beams bonded to each other and anchor bolts on said buttresses for tying said beams thereto.

3. A dam having concrete frame-work constructed *in situ*, decks on said frame-work consisting of separately molded concrete beams, each beam having a recess in the longitudinal corners of its face, the abutting recesses in said beams being adapted to form key ways, and grouting material in said key ways and between said beams for bonding the same together.

4. A dam having buttresses of any suitable material provided with a toe, heel and crown, separately molded concrete beams formed with abutting anchor recesses, like recesses in the toe, heel and crown and grouting for bonding the parts together.

5. A dam having buttresses formed with corrugated bearing faces, decks on said buttresses consisting of separately molded concrete beams, each beam having a recess in the longitudinal corners of its face abutting a like recess in the adjacent beams, and grouting material in said recesses and between said beams and buttresses for bonding the same together.

6. A dam having a plurality of buttresses built *in situ*, decks consisting of separately molded concrete beams overlapping at their ends on said buttresses, each beam having a recess in the longitudinal corners of its face, the adjoining recesses in said beams being adapted to form key ways, a grouting material in said key ways, between each of said beams and between said beams and buttresses, a spacing sheet between one end of each beam and its supporting buttress, and a compression plate at said end of each beam.

7. A dam having a plurality of concrete buttresses, decks on said buttresses consisting of separately molded concrete beams bonded to each other and anchored to said buttresses by means of bolts embedded therein, said beams being slidable at one end on

the buttresses to permit expansion and contraction.

8. A dam having a plurality of buttresses, decks consisting of separately molded concrete beams resting at their ends on said buttresses, each beam having a recess in the longitudinal corners of its face, the adjoining recesses in said beams being adapted to form key ways, U bolts embedded at intervals in said buttresses, clips secured to said U bolts, anchor bolts in said clips, means for securing said beams to said bolts and a grouting material in said key ways between each of said beams and between said beams and buttresses.

9. A dam having a plurality of concrete buttresses, decks on said buttresses consisting of separately molded concrete beams, said beams being spaced apart at their ends and sides and slideable at one of their ends on their supporting buttresses, anchor bolts secured to said buttresses, a looped rod embedded in each end of said beams, said rods in abutting beams being adapted to receive an anchor bolt, nuts on said bolts for retaining said rods in position thereon, a resilient wrapper for the looped rods in the slideable ends of said beams and grouting for bonding the beams to each other and to the base and crown of said buttresses.

10. A dam having a plurality of buttresses built *in situ*, decks consisting of individually molded concrete beams supported at their ends on said buttresses, each beam having a recess in the longitudinal corners of its face, the adjoining recesses in said beams being adapted to form key ways, a spacing sheet between one end of each beam and its supporting buttress, a compression plate at the same end of each beam, U bolts embedded at intervals in said buttresses, clips secured to said U bolts, anchor bolts attached to said clips, a looped rod embedded in each end of said beams, the rods in abutting beams being adapted to receive one of said anchor bolts, nuts on said bolt for securing said rods thereto and grouting in said key ways, between each of said beams and between said beams and buttresses.

In testimony whereof, I have signed my name to this specification in the presence of two subscribing witnesses.

GEORGE W. FREEMAN.
